No. 37,462.

Patented June 13, 1905.

UNITED STATES PATENT OFFICE.

WILLIAM H. REDMOND, OF BIG RAPIDS, MICHIGAN, ASSIGNOR TO THE LUCE-REDMOND CHAIR COMPANY, LIMITED, OF BIG RAPIDS, MICHIGAN, A CORPORATION OF MICHIGAN.

DESIGN FOR A CHAIR-FRAME.

SPECIFICATION forming part of Design No. 37,462, dated June 13, 1905.

Application filed April 3, 1905. Serial No. 253,668. Term of patent 7 years.

To all whom it may concern:

Be it known that I, WILLIAM H. REDMOND, a citizen of the United States, residing at Big Rapids, in the county of Mecosta and State of Michigan, have invented a new, original, and ornamental Design for a Chair-Frame, of which the following is a specification, reference being had to the accompanying drawing, forming part thereof.

The figure is a perspective of a chair-frame, showing my new design.

I claim—

The ornamental design for a chair-frame, as shown.

WILLIAM H. REDMOND.
